UNITED STATES PATENT OFFICE.

JOHN N. DERSCHUG, OF SYRACUSE, NEW YORK, ASSIGNOR TO SYRACUSE WASHING MACHINE CORPORATION, OF SYRACUSE, NEW YORK, A CORPORATION OF DELAWARE.

CLOTHES-WASHING MACHINE.

Original application filed January 31, 1920, Serial No. 355,515. Divided and this application filed November 10, 1923. Serial No. 673,952.

This invention relates to certain improvements in clothes washing machines and refers more particularly to the driving means for the washing and wringing mechanism and to the relation of said driving means and mechanisms to the frame and tub of the machine as a division of my Patent 1,480,157, Jan. 8, 1924.

The main object of my present invention is to increase the general working efficiency of the various parts of a machine of this type by securing the power plant and main gear housings to the under side of the tub-supporting platform of the machine frame so that the driving connections for the washing and wringing mechanisms may be brought into more compact and balanced relation to the axes of movement of said mechanism. Another object is to support the wringer near one of the legs of the tripod in such manner that it may be swung to different positions over and away from the top of the vat without liability of overturning the machine, thereby avoiding the use of extra means of support for this purpose.

A further object is to assemble the various mechanisms upon the machine in such manner as to avoid excessive vibration thereof when in operation.

A still further object is to support the vat on the frame in such manner that it may be readily removed without disturbing any of the other mechanisms except the removal of the yoke with the dashers thereon and the post.

Other objects and uses relating to other specific parts of the machine will be brought out in the following description.

In the drawings:—

Figure 1 is a top plan of a clothes washing machine embodying the various features of my invention.

Figure 2 is a transverse vertical sectional view of the same machine taken on line 2—2, Figure 1.

Figure 3 is a top plan of the mechanism underlying the vat, a portion of the supporting bed therefor being broken away.

Figure 4 is an enlarged vertical sectional view taken on line 4—4, Figure 3, showing means for transmitting motion from the motor shaft to the horizontal counter shaft

from which power is transmitted to the dashers and to the wringer.

Figure 5 is an enlarged sectional view taken on line 5—5, Figure 3.

Figures 6 and 7 are enlarged vertical sectional views taken respectively on lines 6—6, and 7—7, Figure 1.

Figure 8 is an enlarged horizontal sectional view taken on line 8—8, Figure 2.

Figure 9 is a horizontal sectional view taken in the plane of line 9—9, Figure 7.

The machine, as illustrated, comprises a main supporting frame —1— having a circular platform —2— disposed in a substantially horizontal plane and supported by a series of, in this instance, three upright legs —3— in uniformly spaced relation circumferentially or at the angles of an equilateral triangle, said legs being extended some distance above and below the plane of the platform —2—, and are secured to said platform by bolts —4—.

A circular band or ring —5— is secured by bolts —6— to the inner faces of the upper ends of the legs —3— to assist the platform —2— in holding the legs in fixed relation to each other and to said platform, said legs being preferably made of channel irons with their channels facing inwardly for imparting additional rigidity and strength thereto.

The upper ends of the inwardly projecting ribs of the legs —3— are recessed at —7— to form shoulders —8— which are engaged by the lower edges of the ring or band —5— to further stiffen the frame against torsional strains and at the same time affording a more positive connection between the band —5— and legs.

The lower ends of the legs are mounted upon suitable casters —9— each of which comprises a bracket —10— secured to its leg.

A circular vat —20— is supported directly upon the platform —2— within the legs —3— and ring or band —5— so that it may be readily removed by upward displacement and is provided with a suitable lid or cover —21— loosely resting upon its upper edge.

The major portion of the vat is preferably made of non-corrodible sheet metal but in order that the washing operation and action of the interior mechanism may be inspected from time to time, one side of the vat is pro-

vided with a transparent panel —22— of glass or other suitable material made to conform to the curvature of the main body and has its edges suitably held against the inner faces of the marginal edges of the opening by internal flanges —23— which may be brazed or otherwise secured to the main body of the vat around the edges of the opening in which the glass panel —22— is inserted.

10 The cover or lid —21— is also provided with a central circular panel —24— of glass or other transparent material suitably held against the inner face of the metallic portion of the cover by flanges —25— which are 15 clamped to the metallic portion by bolts or screws —26—, Figure 2.

A tubular post —27— is secured at its lower end to the center of the platform —2— and the bottom of the vat —20— and rises 20 some distance above the bottom of said vat for receiving and guiding a vertically movable plunger —29— hereinafter described, said post being provided near its lower end with an annular flange —30— resting upon 25 the upper face of the bottom of the vat and secured thereto in the manner shown in my patent previously referred to, said post being surrounded by a lower sleeve —35— to prevent winding of the clothes on the stationary 30 post.

35 A perforated sheet metal plate —40— of substantially the same diameter as that of the interior of the vat is supported in said vat a short distance above and in fixed relation to the bottom thereof by means of suitable feet or projections —41— on the lower side of the plate, which is provided with a series of perforations —42—.

40 This perforated plate constitutes what may be termed a false bottom having its central portion provided with an opening for receiving the post —27— and allowing the said central portion to rest upon the base of the post, which additionally holds it in spaced relation to the bottom of the vat.

45 The object of this perforated plate is to allow the water to pass therethrough from the bottom upward and also from the top downward, which permits the clothes which rest thereon to be more thoroughly washed by the vertical reciprocatory dashers by reason of the fact that the water is free to pass entirely through the clothes in reverse directions as produced by the suction and pressure of the dasher cups hereinafter more fully described.

50 The plunger —29— is preferably tubular and extends entirely through and beyond the ends of the post —27— in which it is guided in its vertical movement.

55 A yoke —43— is adjustably mounted upon the upper end of the plunger —29— and is held in its adjusted position by a removable locking bolt —44— which is adapted to enter 60 in one of the series of openings —45— one

above the other in the plunger some distance above the upper end of the post —27— for supporting the dashers at different heights relative to said post or rather relative to the bottom of the vat, said locking bolt being 70 held in its locking position by means of a spring —46— which is pivoted at —47— to the yoke some distance to one side of the plunger so that the spring —46— may be moved into and out of engagement with the 75 adjacent end of the locking bolt —44— for permitting the insertion and removal thereof into and from the apertures in the hub of the yoke.

This yoke is provided with opposite downwardly curved arms —48— to better resist the upward thrust strains to which the outer ends thereof carrying the dashers are subjected, particularly when said dashers are brought downwardly with considerable force 80 on the clothes lying on the perforated plate —40—.

These arms —48— are of substantially equal length and are provided at their outer ends with tubular heads —49— open at the 90 bottom for receiving the reduced ends or hubs —50— of a pair of dashers —51—.

Plunger reciprocating mechanism.

A collar —61— is loosely mounted upon 95 the lower end of the plunger —29— to permit the latter to turn therein, said plunger being provided with a ratchet wheel —63— for a purpose hereinafter described.

This collar is provided with pendent apertured lugs —66— for receiving a pivotal pin —67— which projects beyond the outer faces of the lugs for receiving and supporting a pair of links —68—, the latter being held in place by cotter pins —69—, to permit the parts to be readily detached when necessary.

These lower ends of the links —68— are pivotally connected by a pin —71— to one end of a vertically movable rocking lever 100 —73— having its opposite end pivoted at —74— to a bracket —75— which is secured to the under side of the platform or vat-supporting bed —2—, said lever having its intermediate portion connected by a pitman 110 —76— to a crank arm —77— on one end of a rotary shaft section —78— having its axis disposed at right angles to the plane of movement of the lever —73—, as shown more clearly in Figures 2, 3 and 5.

115 This shaft section —78— is loosely journaled in one end of a revolvable sleeve or tubular counter shaft —79— which is journaled in bearings —80— and —81— forming parts of separate gear cases —82— and —83— both of 120 which are secured to the underside of the bed plate or platform —2— as shown more clearly in Figure 5, said shaft section —78— being provided with an annular groove —84— for receiving a pair of diametrically opposite re- 125

ainers —85— which are secured by screws —86— to the adjacent sides of the sleeve or counter shaft —79— and serve to hold the shaft section —78— against endwise movement relatively to said counter shaft.

- The inner end of the shaft section —78— is provided with a clutch face —87— cooperating with a companion clutch face —88— on the adjacent end of a clutch section —89—
- 10 within the sleeve —79—, the intermediate portion of said clutch section —89— being provided with a diametrical slot —90— there through for receiving a key or pin —91— which is secured to the opposite walls of the
- 15 sleeve —79— and serves to transmit rotary motion from said sleeve to the clutch section —89— and to allow the clutch section to be moved axially within the sleeve for engaging and disengaging its clutch face —88— with
- 20 and from the companion clutch face —87— of the shaft section —78—.

A spindle —92— coaxial with the sleeve —79— is loosely journaled at one end in a bushing —93— in the outer end of the clutch section —89— and extends outwardly through a gear —94— on the outer end of said sleeve, the inner end of the spindle being provided with a head —95— interposed between the inner end of the bushing and end wall of a

25 socket —96— in which the head is rotatable to hold the clutch section and spindle against relative endwise movement and at the same time permitting relative rotation of the clutch section and spindle.

30 The outer end of the spindle —92— is provided with a grooved collar —97— for engagement by a shifting arm —98— which is secured to a rock shaft —99— in the gear case —83— one end of said rock shaft being ex-

35 tended through a suitable opening in the gear case and is secured to a hand lever —100— by which the shifting member —98— may be rocked in reverse directions for throwing the clutch section —89— into and out of engagement with the shaft section —78— to start and stop the reciprocation of the plunger —29— carrying the dashers —51—.

The means for transmitting motion to the counter shaft or sleeve —79— comprises an

40 electric motor—A—having its frame suitably secured to the underside of the bed plate or platform —2— and having its motor shaft as —a— disposed horizontally at right angles to the axis of the counter shaft —79— as

45 shown more clearly in Figure 3, said motor shaft being preferably made in sections coupled together by a universal joint —a'— to compensate for any slight variations in the alignment of the shaft sections.

50 A worm —B— is secured to a motor shaft section —b— which is journaled in suitable bearings —b'— in the gear case —82— and is connected by a universal coupling —C— to a loose disc or collar —c— on the adjacent

55 end of a coaxial motor shaft section —c'—.

The disc —c— which is loose on the shaft section —c'— is connected by a slip clutch —D— to the shaft section —c'— to prevent stalling of the motor in case the load driven by the worm —B— should be excessive, said slip clutch comprising a disc —d— secured by a pin —d'— in spaced relation to the disc —c— to receive between said discs a fibre disc —d'—.

Additional discs —e— are loosely mounted upon the shaft section —c'— between the disc —d— and adjacent end of a coil spring —E— which surrounds the shaft section —c'— and has its outer end abutting against an adjusting screw or nut —e'— which is loose on the shaft section —c'— and is screwed into the adjacent end of an enclosing sleeve —F— to adjust the tension of the spring and thereby regulate the friction between the several discs, the inner end of the sleeve —F— being rigidly secured to the disc —c—.

The worm —B— meshes with a worm gear —f— which is secured by a set screw —f'— to the periphery of the sleeve or countershaft —79— between the opposite end walls of the gear case —82— as shown in Figure 5, the gear —f— coacting with the inner ends of the bearings —80— to hold the sleeve —79— against endwise movement.

It is now clear that when the motor is in operation and the clutch section —89— is forced into engagement with the clutch face —87— of the crank shaft —78— reciprocatory motion will be transmitted to the plunger —29— through the medium of the pitman —76—, lever —73—, link —68— and collar —61— for operating the dashers —51— into and out of engagement with the clothes which may rest upon the perforated plate —40— near the bottom of the vat.

Intermittent rotary motion.

Suitable means is provided for intermittently rotating the plunger and dashers thereon step by step in one and the same direction as the plunger is elevated, and for this purpose is provided the ratchet wheel —63— secured to the lower end of the plunger, in the manner previously described, directly above the collar —61— which has its upper end reduced in diameter to form a journal bearing for a horizontal rocking member —G— carrying a pawl —g— and a radial pin —g'—, the pawl —g— being spring pressed radially into engagement with the teeth of the ratchet wheel —63— to rotate the plunger one or more tooth spaces at a time when the lever —G— is rocked in one direction and to permit said pawl to return freely across the face of the teeth.

A plate —H— is secured to the underside of the bed plate or platform —2— and extends downwardly therefrom, said plate being provided with a diagonal slot having its opposite walls forming cams —h— and

—h'—, the lower end of the slot being open and disposed in the path of the vertically movable pin —g'— to receive said pin as the plunger approaches the limit of its upward movement and to permit it to ride against the cam face —h— for rocking the member —G— and pawl carried thereby for rotating the plunger with the dashers thereon through a limited arc as the pin continues its upward movement along the cam face —h—, the opposite cam face —h'— serving to return the rocking member —G— to its starting position as the plunger is moved downwardly during which latter operation the pawl slides freely 10 across the face of the teeth of the ratchet wheel —63—.

The lower end of the slot in the plate —H— is flared circumferentially to assure the entrance of the pin —g'— into said slot when 20 the plunger is elevated.

Wringer mechanism.

The washing machine is equipped with a suitable wringer —I— adapted to be moved 25 to and from a position across the upper end of the vat —20— and comprises a frame —i'— and a pair of rollers —i— which are adapted to be rotated in reverse directions for feeding the clothes into and out of the vat.

30 The wringer frame —i'— is provided at one end with a gear case —J— having a hub —j— mounted upon the upper end of a stationary supporting post —j'—, as shown in Figures 6 and 7, the lower end of said post 35 being removably mounted on a tubular hub —83— of the gear case —83—.

The wringer frame is preferably made in sections, one section carrying the rollers —i— while the other section is removably mounted 40 upon the upper end of the post —j— by upward displacement, the sections of the wringer being secured together end to end by bolts —i²—.

45 The upper portion of the post —j'— just below the hub —j— may be attached to the circular band —5— or adjacent leg —3— by means of a bracket —K—, which together with the bearing at the lower end of the post serves to hold it rigidly in an upright position, it being held against rotation by any suitable means as, for example, a clamping plate —k— on the bracket —K—.

The portion of the post —j'— within the hub —j— is provided with a series of, in this 55 instance four, radial apertures —k'— arranged equal distances apart circumferentially for receiving a locking bolt —L— which is slidable radially in a socket and in one side of the hub —j— and is spring pressed 60 inwardly into the aperture —k'— which may register therewith to hold the wringer in its adjusted position, the outer end of the pawl or bolt —L— being provided with a handle or knob —M— by which it may be 65 withdrawn outwardly against the action of

its retracting spring to release the wringer frame and to allow it to be turned horizontally about the axis of the post —j'— to and from a position above one side of the tub or vat —20—.

70

The supporting shaft for the lower wringer roll —i— is extended axially and journaled in a suitable bearing —m— in the wringer frame or in one side of the gear case —J— and is provided with a gear —m'— secured 75 thereto within said gear case.

A vertical shaft —N— extends centrally through and beyond the opposite ends of the upright post —j'— and has its lower end journaled in a bearing —83'— in the gear case —83— and its upper end journaled in bearings —n'— in the lower and upper side of the gear case —J—, the lower end of said shaft being provided with a gear —O— meshing with the gear —94— on the countershaft —79—.

80 A pair of beveled gears —o— are loosely mounted upon the upper end of the shaft —N— within the gear case —J— and are normally engaged with the lower and upper 90 faces of the gear —n'—.

The inner ends of the beveled gears —o— are provided with clutch faces —o'— adapted to be engaged by corresponding clutch faces on the ends of an interposed clutch collar —P— which is splined upon the shaft —N— to rotate therewith and to move endwise into and out of engagement with the clutch faces —o'—.

95 A rock shaft —Q— is journaled in a suitable bearing —R— on the outer end of the gear case —J— and is held against endwise movement by an adjusting screw —r— which is engaged in a radial threaded aperture in the bearing —R— and enters an annular groove —r'—. The rock shaft —Q— is provided with an eccentric pin —S— carrying the roller —s— which rides in the annular groove in the collar —P— to adjust said collar axially into and out of engagement with 105 one or the other of the gears —o— according to the direction in which it is desired to rotate the wringer rolls, said rock shaft being provided with a hand piece —q— by which it 110 may be operated.

115

Operation.

The operation briefly described is as follows: Assuming that the motor is in operation, power may be transmitted to the plunger 120 for reciprocating the dashers —51— vertically by simply throwing the clutch —88— to locking engagement with the companion clutch —87— by means of the hand lever —100—.

125

This operation may be effected without operating the wringer mechanism, which on the other hand may be operated in either direction independently of the plunger by simply shifting the clutch member —P— in one di- 130

rection or the other according to the direction in which it is desired to rotate the wringer rolls, in which case the clutch —88— would be withdrawn from engagement with its companion clutch —87—.

Or, if desired, both the plunger and the wringer mechanism may be brought into action simultaneously by the proper adjustment of both of the clutches —88— and 10 —P—.

The operations and functions of the various other parts have been clearly defined in the foregoing description and while the construction shown is particularly simple, efficient and economical, I do not wish to limit 15 myself to that specific construction.

I claim:

1. Operating means for mechanical clothes washing machines having a vertically reciprocating plunger, and a lever movable about a horizontal axis for reciprocating said plunger, a gear case, a tubular shaft journaled in the gear case, means for rotating the tubular shaft, a crank shaft journaled solely in the tubular shaft and provided with a crank arm, clutch connections between the tubular shaft and crank shaft for stopping and starting the crank shaft, connections between the crank arm and lever for reciprocating the latter when the crank shaft is rotated, and 30 means for holding the crank shaft and tubular shaft against relative endwise movement. 35

2. Operating means for mechanical clothes washing machines having a vertically reciprocating plunger, and a lever movable about a horizontal axis for reciprocating said plunger, a gear case, a tubular shaft journaled in the gear case, means for rotating the tubular shaft, a crank shaft journaled in the tubular shaft and provided with a crank arm, clutch connections between the tubular shaft and crank shaft for stopping and starting the crank shaft, connections between the crank arm and lever for reciprocating the latter when the crank shaft is rotated, and 40 means for holding the crank shaft and tubular shaft against relative endwise movement, said clutch connections including a clutch section 45 slideable endwise of and within the tubular shaft into and out of clutching engagement with the crank shaft and operatively connected to the tubular shaft to rotate therewith, and means for shifting said clutch section. 50

In witness whereof I have hereunto set my hand this 1st day of November, 1923. 55

JOHN N. DERSCHUG.
